Fig. 1.

Fig. 2.

Fig. 3.

FIG. 4

FIG. 5

FIG. 1 is a top plan view of the combination tool showing my new design;

FIG. 2 is a side elevation of the design of FIG. 1;

FIG. 3 is a bottom plan view thereof;

FIG. 4 is a cross-sectional view taken along line 4—4 of FIG. 3; and

FIG. 5 is an exploded view of the combination tool showing the saw separated from the handle.

The handle is divided into an elongated tubing section and a knurled end member which is through screw threadably received within the tubing section. The knurled member has attached thereto a saw blade which is storable within the tubing member. The tubing member is connectable to different heads, such as an axe, a shovel, or a pick, with a connection being established through a removable pin.

I claim:

The ornamental design for a combination tool, substantially as shown and described.
